ACOUSTICAL CORRECTION TILE

Wallace Lanz, New York, N.Y., assignor to Minnesota and Ontario Paper Company, Minneapolis, Minn.

Filed June 12, 1962, Ser. No. 70,517

Term of patent 14 years

(Cl. D18—2)

FIG. 2

FIG. 1

FIG. 3

FIGURE 1 is a top plan view of acoustical correction tile, showing my design.

FIGURE 2 is an edge view of said acoustical correction tile.

FIGURE 3 is a partial sectional view taken along lines 3—3 of FIGURE 1.

The bottom of the tile is substantially plain.

I claim:

The ornamental design for the acoustical correction tile, substantially as shown and described.
